UNITED STATES PATENT OFFICE.

ROY FULLER, OF ST. PAUL, MINNESOTA.

TOY GUN.

1,376,867.

Specification of Letters Patent. Patented May 3, 1921.

Application filed February 21, 1921. Serial No. 446,550.

To all whom it may concern:

Be it known that I, ROY FULLER, a citizen of the United States, residing at St. Paul, in the county of Ramsey and State of Minnesota, have invented a new and useful Toy Gun, of which the following is a specification.

My invention relates to toy pistols and the object is to provide a novel, simple and easily operated device of said class which is practically harmless and provides amusement for young and old in target practice.

In the drawing:

Figure 1 is a top view of the device.

Fig. 2 is a longitudinal sectional elevation on line 2—2 in Fig. 1.

Fig. 3 is a front end view of the pistol.

Fig. 4 is a side view on a reduced scale to show more clearly the arrangement of the rubber bands.

Fig. 5 is Fig. 4 with the arrangement of the rubber band or bands modified.

Referring to the drawing by reference numerals, 5 designates the stock or body of the pistol and may be made of iron, wood or other material and provided with a handle 6.

The barrel or bore 7 extends throughout the entire length of the body and upon the front portion of it is mounted a magazine 8 in which peas or similar projectiles 9 are placed. The top of the magazine is closed by a resilient arm 10 having one end looped at 11 for a headed pivot 12, and the other end bent upward to form a nail catch 13 by which to swing the arm on the pivot so as to open or close the magazine.

Slidable in the bore 7 is a plunger or ejecting rod 14 having its rear end provided with a cross head 15 having a groove 16 and made a little wider than the thickness of the stock so that there will be clearances 17 between the stock and the two strands of an endless rubber band 18 by which the ejector rod is operated; said band engaging in a groove 16 in head 15 and a groove or notch 20 in the front end of the stock.

Slidable in a channel 21 in the lower part of the stock, in which it has some vertical play, is a trigger bar 22 carrying a trigger 23 which projects downwardly through a slot 24 in the stock and is at all times impelled upwardly and forwardly by an endless rubber band 25 (see Fig. 4) engaging a notch 26 in the upper part of the front end of the stock and the rear side of the trigger and is held fairly clear of the sides

of the stock by resting in notches 27 in lateral projections 28 on the trigger. Said trigger bar 22 has its top side provided with a short embossment or rib 29 slideable in a narrow slit 30 in the stock ready to engage with its angular ends the angular terminals of a notch 31 in the lower side of the ejector rod 14. The rear end of the trigger bar is formed with an incline 32 (see Fig. 2) adapted to engage a fixed pin 33 and thereby disengage the trigger bar from the notch 31 at the moment of firing.

In the operation of the device, after the magazine 8 has been loaded the operator holding the handle 6 in the hand pulls the trigger 23 rearwardly by the forefinger of the same hand holding the handle; this pulling retracting the trigger and the ejector rod 14 until the front end of the latter permits one bullet 9 to pass from the magazine into the barrel 7. Further pulling of the trigger brings the incline 32 against pin 33 and disengages the trigger bar from the ejector rod, allowing the latter to be thrown forward by the band 18 and thereby to shoot the bullet a considerable distance through the air. As soon as the pulling on the trigger is released the rubber band 25 will restore the trigger rod to engaged position with the notch 31 in ejector rod 14 and thus the pistol is ready for the next pull at the trigger.

In the modification Fig. 5 the rubber bands are only one endless band forming the strands 18^a and 25^a at each side of the stock. To enable strand 25^a to increase the shooting force of strand 18^a the band is movable over a roller 34 rotating on a stud 35, the arrangement shown in Fig. 5 being of course the same on both sides of the pistol. If the gun is one of considerable length and strong force the strand 25^a may be an inelastic cord secured at 36 to a very strong elastic band 18^a.

In the manufacture of the pistol the same may have its main body formed of a right and a left half divided centrally and secured together by screws or in a cheaper grade by rivets 37. This is especially convenient when the pistol is made of wood, since the bore 7 and channels 21 and slots 24 and 30 may then be planed or milled out cheaply half and half in each part before the parts are secured together. The plunger 14 may have the top side of its front end slightly beveled as at 19 so that when a small bullet

is crowded by a larger one, that part of the larger bullet projecting into the bore will be pushed back by bevel 19 when the firing takes place.

5. What I claim is:

1. In a gun of the class described, a stock having a bore extending throughout its entire length to form a barrel and having below said barrel a longitudinal channel with
- 10 an upward slit extending into the bore and a downward slit for a trigger, an ejector rod slideable in the barrel and having at its rear end a notched head adapted to stop against the rear end of the stock, a rubber
- 15 cord engaging in the notch of the head and extending at both sides of the stock and attached to the front end of it, said rod having in its lower side a notch; a trigger movable in the lower slit and having a rod slideable
- 20 in the channel with some vertical play therein, and provided with a lug arranged to engage in the notch of the rod to pull it rearwardly and to limit the forward movement

of the trigger bar, elastic means for holding said trigger bar normally upward and forward, and automatic means for disengaging it from the ejector bar when pulled to firing position, and a magazine arranged to automatically feed bullets into the barrel in front of the ejector rod whenever the latter is retracted.

2. The structure specified in claim 1, and means for holding the elastic elements clear of the sides of the stock to prevent chafing and friction.

3. The structure specified in claim 1, said magazine comprising a vertical tube fixed upon the top of the barrel and opening into the same, and having a pivoted swingable keeper upon its top to prevent escape of the 40 bullets.

4. The structure specified in claim 1, said ejector rod having the top side of its front end beveled, for the purpose set forth.

In testimony whereof I affix my signature. 45
ROY FULLER.
